UNITED STATES PATENT OFFICE.

CINCO S. ODA, OF BOSTON, MASSACHUSETTS, ASSIGNOR OF ONE-HALF TO PETER N. FISHER, OF BOSTON, MASSACHUSETTS.

PENNANT EMBODYING PICTURE FRAME.

Application filed January 26, 1921. Serial No. 440,100.

To all whom it may concern.

Be it known that I, CINCO S. ODA, a subject of the Emperor of Japan, residing at Boston, in the county of Suffolk and State 5 of Massachusetts, have invented certain new and useful Improvements in Pennant Embodying Picture Frames, of which the following is a specification.

This invention relates to pennants, and the 10 primary object of the invention is to provide an improved means for supporting and holding a picture or photograph upon the pennant body, so that one of the college athlete's picture may be made a part of 15 the pennant.

A further object of the invention is to provide an improved means for detachably holding a picture in position on a pennant body so that the same can be removed and 20 another substituted therefor when desired.

A still further object of the invention is to provide an improved pennant having a picture frame and picture associated therewith which is formed of flexible material, so as to 25 permit the waving of the pennant on a field or other place of college or fraternity activities.

A still further object of the invention is to provide an improved device of the above 30 character which is durable and efficient in use, one that is simple and easy to manufacture, and one which can be placed upon the market at a reasonable cost.

Other objects of the invention will appear 35 in the following detailed description taken in connection with the drawings, in which drawings:

Figure 1 is a perspective view of the 40 improved pennant and picture frame.

Figure 2 is a fragmentary detail enlarged 45 view of the pennant and picture frame, showing a portion of the same in raised position, illustrating the manner of attaching the frame to the pennant.

Figure 3 is a detail enlarged vertical section through the pennant and frame.

Figure 4 is a fragmentary enlarged rear elevation of the improved pennant showing 50 the means of positioning the picture in the improved frame.

Referring to the drawings, in detail, wherein similar reference characters designate corresponding parts throughout the 55 several views, the letter A indicates the improved pennant having a picture frame B

associated therewith for the reception of a picture or photograph C.

The pennant A includes a body 5 formed of flexible material such as felt or the like having the usual triangular shape, but it is 60 to be understood that the same may be made in any preferred shape or form and the body 5 is provided with the name 6 of the college, fraternity or other organization. The inner edge of the pennant body 5 is provided with 65 a reinforcing strip 7 having the usual attaching strips 8 secured thereto whereby the pennant may be attached to a pole or cane 9.

The frame B includes substantially rectangular open body 10, which is secured at 70 its outer edge to the pennant body by suitable stitches 11. By stitching the outer edge of the open body 10 to the body 5 of the pennant, inwardly extending free flanges 12 are provided behind which the picture C is 75 adapted to be confined. A flexible thin strip or film of celluloid, isinglass or the like may be positioned in front of the picture C and engagement with the inwardly extending flanges 12, for forming a protection for the 80 picture C and if so desired, the transparent strip 13 may be secured by suitable stitches 14 to the inner edge of the flanges 12 of the frame 10.

The body 5 of the pennant A is provided 85 with a horizontal slit 15 which extends substantially the width of the open body 10 adjacent to the upper end thereof and forms means whereby the picture C may be readily inserted in the pocket formed by the body 5 90 of the pennant and the opened body 10 of the frame.

The picture C is preferably printed on 95 relatively thin flexible paper and may be of any desired member of a foot ball team, or other notable of the college or other organization. Owing to the extreme simplicity of the frame, and the fact that only one additional ply of material is necessary to form the frame, the frame may be made 100 very cheaply and the relative thinness of the frame and pennant will permit the same to readily flex, to permit the pennant or banner to be rolled or waved upon a field when desired.

Changes in details may be made without departing from the spirit or scope of my invention; but,

I claim:

A display device comprising a main body 110

portion of fabric capable of being readily flexed or waved, a relatively smaller frame of fabric capable of being readily flexed or waved, said frame having a sight opening 5 and secured to the main body portion at the outer margin of the frame, said main body portion having a slit adjacent one of the margins of the frame providing an opening

from the back of the main body portion to the rear of the frame, and a photograph or 10 like picture on material capable of being flexed or waved disposed between said main body portion and frame, the photograph or like picture being visible through the sight opening of the frame.

CINCO S. ODA.
